AKTIEESLSKAB, OF CHRISTIANIA, NORWAY.

PRODUCTION OF COMMERCIALLY-PURE NITRATES.

1,115,164.

Specification of Letters Patent. Patented Oct. 27, 1914.

Application filed June 22, 1909. Serial No. 503,638.

To all whom it may concern.

Be it known that we, CARL BOSCH and WILHELM WILD, doctors of philosophy and chemists, subjects, respectively, of the King of Prussia and the Grand Duke of Baden, residing at Ludwigshafen - on - the - Rhine, Germany, have invented new and useful Improvements in the Production of Commercially-Pure Nitrates, of which the following is a specification.

Our invention relates to the production of commercially pure nitrates by direct absorption of oxids of nitrogen by means of a hot dry absorbent.

The method hitherto adopted of producing commercially pure nitrates from gas mixtures containing oxids of nitrogen, such as are produced, for instance, by treating air in an electric arc flame, has consisted in treating the said mixtures with water, thus obtaining a dilute solution of nitric acid, and then neutralizing this dilute acid with a base, such for instance as soda or lime. A direct absorption of the oxids of nitrogen by a base has hitherto led to mixtures of nitrate and nitrite.

We have discovered that commercially pure nitrate can be obtained, if limited quantities of water vapor be added to the gaseous mixtures containing the oxids of nitrogen and the gases thus treated be then passed over solid basic substances, such as the oxids, hydroxids, and carbonates of the alkaline earth metals, while maintaining these at such a temperature that the water set free during the combination of the gaseous nitric acid with the base remains in the state of vapor. The temperature should not be above about 300° C., since otherwise the compound formed is liable in the presence of moisture to melt, and thus cover up the remainder of the absorbing material and prevent the proper further absorption from taking place. Instead of treating the gases with steam, finely divided water can be added, but it is feared that the final temperature of the gases shall be above the boiling point of nitric acid, as then no liquid nitric acid separates out and, in consequence, metallic vessels can be employed. After the gaseous mixture containing oxids of nitrogen has been treated with steam, or water, as afore-

said, it contains nitric acid, either as such, or in a state of dissociation, but this latter state is not disadvantageous, since in either case the subsequent absorption takes place very rapidly and leads to the production of practically pure nitrate.

The drawing accompanying this specification represents in vertical section an apparatus suitable for carrying out our invention.

In this apparatus the gases pass through the pipe A while the necessary quantity of steam or water vapor is allowed to enter through the pipe B and the valve C, the mixture being then led into the vessel D, which contains the absorbent material EE, (for instance lime) resting on a grating F. The gases pass downward through the absorbing material and then upward by means of the pipe G into a second similar vessel. We prefer to employ a number of such vessels, for instance eight, situated one after the other in series. Each vessel should of course be so constructed that the contents thereof can be easily removed and renewed as soon as they are sufficiently saturated with the nitrous gases. The whole series of vessels is preferably embedded in heat-insulating material, so that the heat is conserved as much as possible, and the requisite temperature for carrying out the process is maintained.

K, K are openings for introducing the absorbing material and L, L are openings for removing the resulting product.

The following example will serve to illustrate further the nature of our invention, but we desire to emphasize particularly the fact that this example is only illustrative of methods of carrying out our invention, and the invention is in no way whatever confined to the example given.

Example. Pass hot gases containing two per cent. of nitric acid through a comparatively large reaction chamber and during the passage add so much steam or finely divided water that each cubic meter of the gases leaving the reaction chamber contains about twenty grams or more of water. Then pass these gases at a temperature of about two hundred degrees centigrade over briquets of slaked lime. The gaseous nitric acid which has been formed is absorbed with

great avidity and after a few days a product containing over ten per cent. of nitrogen is produced.

Now what we claim is:—

- 5 1. The process of producing commercially pure nitrate from gases containing oxids of nitrogen which consists in adding limited quantities of water to the gases and then bringing them into contact with an oxygen
- 10 compound of the alkaline earth series while maintaining a temperature about 280° C. to about 300° C. that the water set free during the absorption remains in the gaseous state substantially as hereinbefore described.
- 15 2. The process of producing commercially pure calcium nitrate from gases contain-

ing oxids of nitrogen which consists in adding limited quantities of water to the gases and then bringing them into contact with lime while maintaining a temperature about 20 280° C. to about 300° C. that the water set free during the absorption remains in the gaseous state substantially as hereinbefore described.

In testimony whereof we have hereunto set our hands in the presence of two subscribing witnesses.

CARL BOSCH.
WILHELM WILD.
